PNEUMATIC RELAY

Louis M. Puster and Joseph P. Wagner, Knoxville, Tenn.,
assignors to Robershaw Controls Company, a corpora-
tion of Delaware

Filed May 24, 1961, Ser. No. 112,387
1 Claim. (Cl. 137—625.66)

The present invention relates to control valves and more
particularly to a condition responsive diaphragm operated
pneumatic relay. 10

An object of this invention is to control the flow of
fluid under pressure into and out of a pneumatic relay
in accordance with a variable condition. 15

Another object of this invention is to connect a source
of pressurized fluid to a pneumatically operated device
in accordance with a condition. 15

Another object of the invention is to prevent the flow
of fluid under pressure from a source through the relay
in accordance with a condition. 20

These and other objects and advantages will become
apparent from the following description taken in connec-
tion with the accompanying drawings in which:

FIG. 1 is a front elevation of the relay of the invention;

FIG. 2 is a section taken substantially along the line
II—II of FIG. 1 but staggered to include offcenter details;

FIG. 3 is a front elevation of a modification of the relay
of the invention;

FIG. 4 is a section taken substantially along the line
IV—IV of FIG. 3 but staggered to include offcenter de-
tails; and

FIGS. 5 and 6 are schematic diagrams of systems em-
bodying the devices of FIGS. 1—4.

The device of this invention may briefly be described
as a relay provided with a supply port, an outlet port,
a vent port, a diaphragm pressure port, and a valving
element movable between positions for controlling the
flow of pressurized fluid into and out of the relay in ac-
cordance with a pressure condition at the diaphragm pres-
sure port.

Referring now more particularly to the drawings, FIGS.
1 and 2 show a relay 10 comprised of a body 12, a cover
14, and a bottom cap 16. A supply port 18, an outlet port
20, and a vent port 22 are respectively formed in the
body 12 and communicate with a plurality of chambers
within the relay to be more fully described hereinafter. A
signal pressure port 24 is formed in the cover 14 and like-
wise communicates with an interior chamber.

The supply port 18 communicates by means of a lateral
passage 26 with a substantially cylindrical supply chamber
28 formed in the lower portion of the body 12. An outlet
chamber 32 is formed by a reduced passage which
extends axially of the supply chamber 28 and defines a
shoulder 30 therebetween. An annular valve seat 34 is
formed on the shoulder 30.

A guide bushing 36, comprising an enlarged base portion
38 and a tubular neck portion 40 of reduced diameter,
is positioned within a recess 42 in the wall of the supply
chamber 28 and extends therein in coaxial alignment with
the chamber 32. A circular valve poppet 44, including a
stem portion 46 and an enlarged head portion 48, is pro-
vided with a circular recess in the upper surface thereof
adapted to receive a relatively soft valve insert 50 there-
in. The stem portion 46 is reciprocable within the tubular
portion 40 and the insert 50 is adapted to cooperate with
the annular valve seat 34 for controlling flow of fluid
therethrough. A light poppet spring 52 encircles the tubu-
lar guide portion 40 and is compressed between the base
portion 38 and the underside of the valve poppet head
portion 48. Communication between the outlet chamber
32 and the outlet port 20 is afforded by means of a lat-
erally extending passage 54.

2

The vent port 22 communicates with an enlarged vent
chamber 56 formed in the upper portion of the body 12
coaxial with the chamber 32. The vent chamber 56 re-
ceives a valve element 58 comprising a tubular stem por-
tion 60 which extends into chamber 32 and is formed with
a valve seat 62 on the end thereof and an actuating plate
64 on the opposite end thereof. A cross-drilled orifice 66
in the hollow stem portion 60 provides communication
between the vent chamber 56 and the control chamber 32.

A valve spring 68 encompasses the valve element 58
within the vent chamber 56 and is compressed between a
shouldered spring seat washer 70, seated on the bottom
of the vent chamber 56, and the underside of the actuating
plate 64. The spring seat washer 70 is annular and
the stem portion 60 extends therethrough. An O-ring seal
71 is positioned around the stem 60 between the spring
seat washer 70 and the body 12 to effect a seal between
the vent chamber 56 and the control chamber 32.

A diaphragm element 72 extends across the upper sur-
face of the relay body 12 forming a flexible wall for the
vent chamber 56 and also a sealing means between the
relay body 12 and the cover portion 14. The central por-
tion of the diaphragm 72 overlies the upper surface of
the actuator plate 64 but it is to be understood that no
connection between these elements is necessary or desired.

A shallow recess, formed in the lower face of the cover
14, provides a signal pressure chamber 74 overlying the
diaphragm 72. The chamber 74 communicates with the
diaphragm pressure port 24 by means of a lateral passage
76 and a perpendicular port 77.

A gasket 78, positioned between the lower face of the
relay body 12 and the bottom cap 16, forms a pressure
seal therebetween and appropriate assembly screws 80
are used to retain the several elements of the relay 10 in
the assembled relation. Suitable mounting brackets 82
are secured to the cover 14 and bottom cap 16, respec-
tively, and provide for panel mounting of the device.

Referring to FIGS. 3 and 4, a modification of the relay
10 is shown. In the modified embodiment, the passage
154, between the control port 120 and the control cham-
ber 132, is extended laterally into the body 112 beyond
the control chamber 132 a sufficient distance to intersect
the vertically extending passage 184 which has a smaller
diameter than passage 154. This passage 184, formed in
the relay body 112, connects the control chamber 132
with the diaphragm pressure chamber 174. The passage
184 extends through the relay body 112 and connects with
an appropriate opening 192 in the diaphragm 172 and is
in alignment with a corresponding passage 194 in the
cover 114.

A substantially hollow orifice screw 186, positioned
in the fluid passage 176 connecting the signal pressure
port 124 and the fluid passage 184, is provided with a re-
stricting orifice 188 in the sidewall thereof. A tapered
shoulder 190, formed adjacent the head portion of the
orifice screw, is adapted to engage a complementary tapered
seat on the cover portion 114 to form a pressure seal
therebetween. An "O" ring seal 191 is fitted within an
annular recess 193 adjacent the innermost end of the ori-
fice screw 186 forming a seal between the orifice screw and
the wall of the fluid passage 176.

Operation

In operation, the relay 10 will be utilized to control
the flow of fluid under pressure from a source through
the supply port 18 to the outlet port 20 in accordance
with the pressure condition above the diaphragm, or to
dead end the supply without permitting passage of fluid
under pressure to the outlet port 20. The path open to
the pressurized fluid will be determined by the pressure
condition existing in the pressure chamber 74. If a fluid
under sufficient pressure is present within the diaphragm

pressure port 24, passage 76, and chamber 74, the diaphragm 72 will be flexed downwardly, thus forcing the actuating plate 64 downwardly against the bias of the spring 68. As the valve element 58 moves downwardly as a result of increased pressure within the chamber 74, the valve seat 62 engages the insert 50 of the valve poppet 44, effecting a seal therebetween and forcing the valve poppet 44 downwardly against the bias of the poppet spring 52. The downward movement of the poppet 44 moves the insert 50 away from engagement with the annular valve seat 34, thus permitting fluid under pressure to pass from the supply port 18 to the outlet port 20 by way of the passage 26, supply chamber 28, control chamber 32, and passage 54 to the outlet port 20.

Simultaneously, the passage of fluid under pressure from outlet chamber 32 to the vent chamber 56 is prevented since the insert 50 has been engaged by the valve seat 62, thus effectively preventing fluid from passing through the orifice 66 of the stem 60 and out into the vent chamber 56. Leakage of pressurized fluid between the outlet chamber 32 and the vent chamber 56 around the stem 60 is precluded by the stem seal 71.

Thus, it may be seen that an increase of signal pressure of a predetermined value on the top of the diaphragm 72 results in opening of the normally closed valve poppet 44 connecting the supply chamber 28 to the outlet chamber 32, while closing the connection between the outlet chamber 32 and the vent chamber 56. Under these conditions, fluid under pressure is permitted to pass from the supply port 18 to the outlet port 20.

If for any reason the pressure existing in the chamber 74 should be reduced or dissipated, the spring 68 will urge the valve element 58 upwardly, thus unseating the stem 60 from the insert 50 and allowing the poppet 44 to move upwardly in response to the spring 52 thus contacting the annular seat 34 and effecting a seal between the supply chamber 28 and the outlet chamber 32. As the valve stem 60 moves away from the insert 50, the control chamber 32 becomes connected to the vent chamber 56 through the orifice 66 of the stem 60 to vent to atmosphere any pressure remaining in the outlet chamber 32. Under these conditions, the supply port 18 and chamber 28 are isolated from the remainder of the relay 10 and remain pressurized.

In the modification shown in FIGS. 3 and 4, existence of a pressure condition of sufficient magnitude on the top of the diaphragm 172 will result in actuation of the relay 100 in the same manner as previously described; however, if the pressure within the recess 174 becomes partially reduced, the valve element 158 will remain in the downward position, thus retaining the communication between the supply chamber 128 and the outlet chamber 132 by supply pressure on the top of the diaphragm 172 through the passage 184 and the restricting orifice 188. It is important to note, however, that if the signal pressure existing on the top of the diaphragm 172 should become completely lost, the quantity of fluid passing through the restricting orifice 188 will be insufficient to retain the valve element 158 in the downward position, thus allowing the diaphragm 172 and valve element 158 to be moved upwardly by the spring 168, seating the valve poppet 148 on the annular seat 134 and sealing the passage 130 between the supply chamber 128 and the outlet chamber 132.

While the pneumatic relays here described may have many and varied applications, their operation will be further understood with reference to a description of FIGS. 5 and 6 wherein simplified pneumatic control systems are utilized to indicate monitored variables of an engine and to shut down the fuel supply to the engine in response to predetermined changes in the variables.

Referring now to the system disclosed in FIG. 5, the system here shown requires the use of the relay 10 shown in FIGS. 1 and 2. A source of fluid under pressure, in

this example an air supply is connected through suitable conduits to the normally closed supply port 18 of the relay 10. Simultaneously fluid under pressure is introduced to the normally closed port 312 of a push button type three way valve 302. It will be understood that at this point no pressure will have been admitted to the system.

In order to actuate the automatic fuel supply valve 304 the push button 303 of valve 302 will be depressed thereby connecting port 312 with port 311 and allowing fluid under pressure to flow through the restricting orifice 301 to the transmitter valve 310, the diaphragm port 24 and the normally closed push button valve 326. Pressure being exerted on the diaphragm of the relay 10 will cause the relay to transfer connecting the supply port 18 to the outlet 20 and thus permit fluid under pressure from the supply to enter the system. At this time pressure will be conducted through suitable conduits to the diaphragm of the normally closed automatic fuel supply valve 304 causing the valve to transfer and connecting the fuel supply to the engine. A manually operable fuel supply valve 306 is also positioned in the fuel supply line for manually controlling the supply of fuel to engine.

In operation once the system is pressurized as described above the push button 303 of the valve 302 is released returning the port 312 to its normally closed position and pressure is maintained throughout the system through the relay 10.

As shown in FIG. 5 the engine protected by this system may be shut down by any of three methods. First the transmitter 310 may sense a variation in the monitored variable condition which exceeds the present limit thus opening the transmitter valve and allowing fluid under pressure to escape from the system in general and the top of the diaphragm of the relay 10 in particular. Upon a loss of pressure or the diaphragm of relay 10, the relay will transfer, closing its supply port 18 and connecting the outlet port 20 to the vent port 22. With the outlet port 20 connected to the vent port 22 pressure previously existing on the diaphragm of the automatic fuel supply valve 304 will be released to atmosphere and the fuel supply valve 306 will transfer thus shutting off the supply of fuel to the engine.

A second method for effecting shutdown of the engine is vent the system to atmosphere by depressing the push button of valve 326. Such action will also serve to vent the diaphragm of relay 10 and the system will shut the engine down as previously described.

A third method for effecting shutdown of the engine would be to manually actuate the manual fuel supply valve 306 to the closed position.

Referring now particularly to FIG. 6 a supply of fluid under pressure, such as compressed air or the like, furnishes the pneumatic pressure for the system and is introduced through suitable conduits to the normally closed supply port 118 of the relay 100. Simultaneously, air is introduced to the normally closed push button type valve 202.

A supply of fuel to the engine is controlled by a diaphragm actuated fuel valve 204 which is shown in its normally closed position and a manually operated fuel valve 206. A pneumatic transmitter valve 210 is employed to respond to some predetermined engine variable such as temperature, pressure, vibration, etc. When the variable is within a safe limit, the transmitter valve 210 is closed. If the variable exceeds the safe limit, the valve 210 opens and pressure within the system is vented to atmosphere through the open valve.

The entire system may be rendered operative upon actuation of the push button type valve 202. Upon opening of the push button valve 202, fluid under pressure is supplied to the transmitter 210 and the system by way of the diaphragm port 124 of the relay 100 and the passage 184 through the restricting orifice 188. Upon the resulting increase in pressure in the recess 174 (FIG. 4), the

diaphragm 172 is deflected downwardly causing the relay 100 to transfer, connecting supply port 118 to the outlet port 120 and blocking the vent port 122. Fluid under pressure may now flow directly from the air supply through the relay 100 to the remainder of the system. The push button valve 202 may be released to assume its normally closed position and pressure will be maintained on top of the diaphragm 172 by an automatic reversal of the flow of air through the passage 184 and restricting orifice 188.

Fluid under pressure is conducted through an appropriate conduit from the relay 100 to the normally closed automatic fuel valve 204 pressurizing the diaphragm of the normally closed fuel valve 204 causing it to transfer. The automatic fuel valve being a normally closed valve, is now transferred to allow fuel to pass therethrough to supply the requirements of the engine.

Assume now that transmitter valve 210 senses a change in the variable condition it is monitoring, which changed condition now exceeds the predetermined safe limit. The sequence of operation to shut down the engine to prevent damage thereto begins immediately and automatically. The transmitter valve 210 senses the unsafe condition and responds thereto by transferring to connect the transmitter supply to the transmitter vent. Pressure entrapped in the system is now allowed to escape through the open transmitter vent.

Pressure is thus allowed to escape from the diaphragm of the automatic fuel valve 204 causing it to transfer to its normally closed positions. With the closure of the valve 204 controlling the supply of engine fuel, the engine is shut down.

The system of FIG. 6 will remain in the condition described until the push button valve 202 is opened to allow a new pulse of air to pressurize the system once again. If upon introduction of new air, the transmitter valve 210 sensing the unsafe condition previously described continues to sense an unsafe condition, the new air will merely escape to atmosphere and the system will remain unpressurized and the engine inoperative.

If, on the other hand, the transmitter valve 210 has reverted to the closed position and sensed a safe condition, the system will become pressurized again as originally described. If it is desired to shut down the engine and render the system inoperative, this may be accomplished quickly and easily by venting the pressure from the system. To accomplish this end, an additional normally closed push button type valve 226 is provided. Actuation of this valve, will result in a drop in pressure on the diaphragm of the relay 100 and a subsequent transfer of the relay 100 to close its supply port 118 to the air supply and automatically connecting the vent port 122 to the outlet port 120 whereby the pressure in the remainder of the system may be vented to atmosphere.

With further reference to FIG. 6, it will be understood that the transmitter 210 may be deleted and the relay 100 in conjunction with valves 202, 226 may be used to remotely or locally control the supply of air to a valve

such as the automatic fuel supply valve 204 with the advantage that if the supply of air to the relay 100 were lost, the relay would transfer to close its supply port 118 and when the air supply was restored the relay 100 would remain closed until it was reopened by depressing push button valve 202. This feature would be particularly important in a system requiring attendance of an operator during start procedures.

It is to be understood that the invention is not limited to the details of construction and arrangement of parts disclosed except within the scope of the appended claim.

What is claimed is:

In a pneumatic relay including a relay body having an inlet port for connection to a source of pressurized fluid, 15 an outlet port, and a vent port, the combination comprising an inlet chamber within said body connected to said inlet port, an outlet chamber within said body connected to said outlet port, a vent chamber within said body connected to said vent port, a passage connecting 20 said inlet chamber and said outlet chamber, a valve seat at the end of said passage within said inlet chamber, first valve means supported within said inlet chamber for movement between open and closed positions, a resilient valve element carried by said first valve for engaging said 25 seat when said valve is in its closed position, a spring means normally urging said valve to its closed position, a second valve having a hollow stem slideable in a bore between said outlet chamber and said vent chamber and extending into said passage, said stem having an opening 30 adjacent the end in said passage arranged to engage and be closed by said resilient valve element, second resilient means normally urging said second valve means to an open position away from said valve element to connect said vent chamber to said outlet chamber through 35 said hollow stem, a signal pressure chamber having an inlet for connection with a variable signal pressure, a diaphragm responsive to the variable signal pressure for moving said second valve against the force of said resilient means from its normally open position to engage 40 and close said opening with said valve element and move said first valve against the force of said spring to disengage said valve element from said seat, and a restricted passage connecting the outlet port with the signal pressure port for augmenting the variable signal pressure with the 45 supply pressure to delay the closing of said control valve upon a subsequent reduction in the signal pressure.
